UNITED STATES PATENT OFFICE.

HARRISON QUINBY, OF MUNCIE, INDIANA, ASSIGNOR OF ONE-HALF TO WILLIAM J. KILLIAN, OF MUNCIE, INDIANA.

UNIVERSAL JOINT.

945,803.

Specification of Letters Patent. Patented Jan. 11, 1910.

Application filed March 3, 1909. Serial No. 481,045.

To all whom it may concern:

Be it known that I, HARRISON QUINBY, a citizen of the United States, and a resident of the city of Muncie, in the county of Delaware and State of Indiana, have invented a new and useful Universal Joint, of which invention the following is a specification.

This invention relates to improvements in universal joints.

10 The objects of my invention are to improve the construction of and to provide a universal joint which will be compact, of few parts, durable, and not liable to get out of repair or adjustment.

15 The objects of my invention are accomplished by and my invention consists in the new construction, combination and arrangement of parts described in this specification, defined in the appended claims, and 20 illustrated in the accompanying drawings.

Corresponding parts are designated by similar characters of reference throughout the several views in the drawings, in which—

25 Figure 1 is a side view and Fig. 2 is an end view of my improved universal joint. Fig. 3 is a side view, the ring being shown in section taken on the line 3—3 Fig. 2. Fig. 4 is a detached enlarged longitudinal 30 sectional view of my invention. Fig. 5 is a detached enlarged longitudinal sectional view of my invention the cap being in raised position. Fig. 6 is a plan view, the cap being removed.

35 The fork-shaped complementary shaft members A have the fork ends A¹ as shown. These shaft members are made of steel and the outer face of each fork end has the semi-spherical recess A² in which will be seated 40 the steel ball B. The structure and dimensions of the shaft members by virtue of my invention may be of the compact form and they will operate in close proximity to each other as shown.

45 The ring C is made of metal of suitable quality, preferably of steel, and is of suitable area in cross section. Extending radially through the ring at the four quarters thereof are the threaded bores D. Each of these bores is terminated externally by the threaded counter bore E having the base E¹ and the ledge E².

In each bore D is screwed the boxing F. The inner end of this boxing has the machined semi-spherical recess F¹ in which the

ball B is seated as shown. The outer end of the boxing F has the recess F² which communicates by the passage F³ with the recess F¹. The annular edge of the outer end of the boxing F is provided with a 60 succession of radially disposed grooves G. The pitch of the threads of this boxing is such that the boxing is capable of being adjusted to proper position with reference to the ball B.

65 Adjacent the threaded wall of the bore D is the well H of suitable depth, and from which well the vertical slot H¹ extends through the wall of the ring. Communicating with and extending horizontally 70 from the upper end of the slot H¹ is the slot H², the function of which will presently be disclosed. Slidably disposed in the well H is the plunger J which has the detent J¹ disposed at such an angle and having its 75 bottom face of such shape as to fit the groove G of the boxing F. The tooth J² is provided on the top of the detent J¹. The guide stud J³ carried by the plunger J fits slidingly in the slot H¹.

80 K designates a coil spring disposed in the well H and underneath the plunger J, and which spring will urge the plunger upwardly.

85 Adapted to close the bore E is the threaded cap L. This cap is threaded as shown and on its bottom face are provided the ratchet teeth L¹.

M M designate recesses to which may be applied a spanner wrench. The distance 90 between these recesses M M is substantially the same as the distance between the annular edges of the boxing, so that the wrench used for moving the boxing may be used to tighten the cap into place.

95 The utility of my invention and the mode of its operation will be apparent from the foregoing description of its construction, and by inspection of the drawings. The only machine work on the shaft members 100 other than the usual bore A³ of the shank of each, are the correctly centered and machined recesses A². To assemble the respective parts the ring C is placed in the position as shown with reference to the shaft members, then the ball B is placed in the recess A². The detent J¹ is then raised and turned to one side and into the bore E, the guide-stud J³ passing into the slot H², as shown by the dotted lines in Fig. 6. The 110

boxing F is then screwed down to proper position of adjustment with the recess F¹ in operative engagement with the ball B. The detent J¹ is then turned back to normal radial position and by the coil spring it will be held in the raised position clear of the boxing and above the grooves G as shown in Fig. 5. As the cap L is being screwed down the ratchet teeth L¹ will engage and pass the tooth J². When the cap has been screwed down into its normal position in contact with the ledge E² there will be the clearance N between the bottom face of the detent J¹ and the base of the groove G as shown in Fig. 4. The formation of the ratchet teeth L¹ with reference to the direction of the thread on the cap is such that any tendency of the cap to move from its tightened position will bring the face of the ratchet tooth into direct engagement with the tooth J². The screwing of the cap down into the position as shown forces the plunger downwardly until the detent J¹ will reside snugly in one of the grooves G. After the placing in position of the other three balls, and boxings and caps, my improved coupling is complete and in readiness for use.

By the construction, combination and arrangement of parts described it will be seen that the cap and the boxing are positively locked against movement from their correct positions, and all fastening means such as keys, lock nuts, set screws and the like are dispensed with and a compact and efficient joint is obtained.

The cavity formed by the recesses F² is intended as a receptacle for lubricant which may be held by a saturated portion of waste deposited in the said cavity; the lubricant will pass through the perforation F³ whereby the ball bearing will at all times be properly lubricated.

To remove the cap L, the guide stud J³ is depressed which moves the tooth J² out of its engagement with the ratchet tooth L¹, the cap may then be unscrewed and removed. The plunger J will be urged upwardly and will occupy the position as shown in Fig. 5, its further upward movement being prevented by the guide stud J³ coming to rest against the top end of the slot H¹. The spanner wrench may be then applied to the grooves G and the position of the boxing may be adjusted.

What I claim as my invention and desire to secure by Letters Patent of the United States, is—

1. A universal joint consisting of a pair of forked complementary shaft members, the outer face of the fork end of each shaft member having a recess therein, a ring member having a radial bore therein to register with each of said fork ends, a bearing member adjustably disposed in each of the said bores and having its inner end recessed, a

ball between each of the fork ends and the adjacent bearing member, a cap at each of the said bores adapted to close the same, means carried by the ring member between the cap and the bearing member which when the cap is tightened into position will lock the cap and the bearing member against movement. 70

2. A universal joint consisting of a pair of forked complementary shaft members, the outer face of the fork end of each shaft member having a recess therein, a ring member having a threaded radial bore therein to register with each of said fork ends, a threaded bearing member adapted to be screwed into each of said bores, having its inner end recessed, a ball between each of the fork ends and the adjacent bearing member, a cap adapted to be screwed into and to close the outer end of each bore, 80 means between and adapted to coengage the cap and the outer end of the bearing member, so that when the cap is tightened into position, the cap and the bearing member will both be locked against movement. 90

3. A universal joint consisting of a pair of forked complementary shaft members, the outer face of the fork end of each shaft member having a recess therein, a ring member having a threaded radial bore therein to register with each of said fork ends the outer end of each of said bores having the threaded counter bore substantially as described, a threaded bearing member adapted to be screwed into each of said bores having 100 its inner end recessed, and its outer end being provided with radial grooves, and there being a central passage connecting the outer end of the bearing member and the recess therein, a ball between each of the fork ends 105 and the adjacent bearing member, a threaded cap adapted to be screwed into the counter bore and having radial depressions on its underside, means carried by the ring member adapted to be urged yieldingly outwardly to coengage the grooves in the outer end of the bearing member and the depressions in the underside of the cap when the latter is tightened into position, substantially as described. 110

4. A universal joint consisting of a pair of forked complementary shaft members, the outer face of the fork end of each shaft member having a recess therein, a ring member having a threaded radial bore therein to register with each of said fork ends, the outer end of each of said bores having the threaded counter bore substantially as described, a threaded bearing member adapted to be screwed into each of the said bores having 125 its inner end recessed and its outer end being provided with radial grooves, a plunger slidingly seated in a well adjacent the bore and having a coil spring thereunder to urge the plunger outwardly, said plunger having 130

a detent thereon to engage the radial grooves of the bearing member and being provided with a tooth on its upper side, there being a stud carried by said plunger and adapted to move slidingly in an L shaped slot therefor in the ring member, a ball between each of the fork ends and the adjacent bearing member, a threaded cap adapted to be screwed into the counter bore and having radial de-
pressions on its underside so that with the

tightening of the cap into position the parts all will be locked against movement.

In testimony whereof I sign my name to this specification in the presence of two subscribing witnesses.

HARRISON QUINBY.
